Invisalign Aligner and Retainer Case, Amazon.com (Year: 2021).*

Primary Examiner — Richard E Chilcot

(57) **CLAIM**

The ornamental design for a dental retainer case, as shown and described.

DESCRIPTION

1. Dental retainer case

1.1 : Perspective

1.2 :Top

1.3 : Back

1.4 : Right

1.5 : Left

1.6 : Bottom

1.7 : Front

FIG. 1.1 is a perspective view of a dental retainer case according to the embodiment of the design; FIG. 1.2 is a side view of a dental retainer case according to the embodiment of the design; FIG. 1.3 is another side view of a dental retainer case according to the embodiment of the design; FIG. 1.4 is a front view of a dental retainer case according to the embodiment of the design; FIG. 1.5 is a rear view of a dental retainer case according to the embodiment of the design; FIG. 1.6 is a top view of a dental retainer case

(Continued)

according to the embodiment of the design; FIG. 1.7 is a bottom view of a dental retainer case according to the embodiment of the design.

1 Claim, 7 Drawing Sheets
